UNITED STATES PATENT OFFICE.

RADCLYFFE FURNESS, OF JENKINTOWN, PENNSYLVANIA.

INGOT MOLD.

Application filed December 31, 1927. Serial No. 243,285.

My invention relates to an improvement in ingot molds.

It has been recognized that in the casting of an ingot it is desirable to have the metal in the mold cool more rapidly in the lower part of the mold than in the upper part in order that shrinkage of the metal on cooling will be compensated for by a feed of metal from the upper to the lower part of the mold.

In order to obtain the desired cooling of the metal in the mold from the bottom, it has heretofore been customary to taper the mold outwardly from the bottom, thus affording a greater wall thickness and consequently greater heat absorption capacity at the bottom of the mold than at the top; and at the same time providing for the reception of a greater volume of metal at the top than at the bottom. It is also customary to taper the outer faces of the walls of the mold inwardly from the bottom to decrease the weight of metal in the walls at the top.

Ingot molds as heretofore constructed have proved not altogether satisfactory in effecting a progressive solidification from the bottom and complete feeding from the top to compensate for the shrinkage, nor has the obvious device of making the taper of the mold section very great produced the desired effect.

In accordance with my invention, I provide an ingot mold having a metal receiving cavity, the lower portion of which has a given contour and the upper portion of which, in extent preferably not substantially less than one-third of the length of the cavity, is enlarged as a result of change in contour resulting in a reduction in the ratio of perimeter to area in the upper portion. For example, the mold in accordance with my invention preferably has a cavity, the contour of the lower portion of which is concave polygonal in cross section and the upper portion of which is enlarged by changing the contour of the polygonal cross section to that of a polygon having because of its shape a less ratio of perimeter to area than that of the lower portion, which may be accomplished by reducing the concavity of the polygonal contour, changing it to convex, or by increasing the number of sides up to the production of a circular contour.

Having now indicated in a general way the nature and purpose of my invention, I will proceed to a detailed description of a pre-

ferred embodiment thereof, with reference to the accompanying drawings in which:

Fig. 1 is a top view of a mold embodying my invention;

Fig. 2 is a vertical sectional view of the mold taken on line 2—2, Fig. 1.

Fig. 3 is a partial bottom view of the mold.

In the several figures 2 indicates an open bottom mold body having a metal receiving cavity 5 and adapted in use to be placed on a sprue plate, not shown, it being understood that my invention is applicable to molds of other types than that illustrated, as for example, closed bottom molds. The lower portion of the cavity 5 is of polygonal contour in cross section, for example, octagonal as shown in Figs. 1 and 3, and the walls 4 of the lower portion of the cavity are preferably made convex, as shown in Figs. 1 and 3, in order to prevent bursting, by ferrostatic pressure from above. The initial skin formed by chilling of the steel against the side of the mold and the contour of the cavity is thus concave polygonal in cross section. The top of the cavity 5 is circular in cross section, as shown at 8, Figs. 1 and 2, while the contour of the upper portion of the cavity adjacent the top varies in cross section resultant from a progressive change from polygonal to circular contour in the upward extension of the cavity, as indicated at 10, Figs. 1 and 2.

The walls 4 of the lower portion of the cavity 5, which, for example, is octagonal in cross section, taper outwardly in their upward extension. The walls of the upper portion of the cavity in which the cross sectional contour varies also taper outwardly in their upward extension and to a greater degree than do the walls 4, however, it will be noted that the cavity on its extreme diameters tapers continuously with an unchanged taper from the bottom to the circular portion, on lines formed at the juncture of adjacent walls as shown at 6 in the several figures. However, it will be appreciated that the taper of the cavity on its extreme diameters may be varied in different portions of its length without departing from my invention.

It will be understood that it is not essential that the cross sectional contour of the cavity at the top be circular, since the benefits of my invention may be substantially had by changing the cross sectional contour of the upper portion of the cavity from, for example, a polygon of a certain number of sides to a polygon of an increased number of sides, or

by gradually changing the contour from concave to less concave, straight, or convex.

As a result of my invention a mold is provided having an increased wall thickness in its lower portion and a decreased wall thickness with increased capacity in its upper portion, whereby progressive cooling of an ingot from the bottom and effective feed of metal from the top to compensate for shrinkage is insured to a degree hitherto unattained.

Having now fully described my invention, what I claim and desire to protect by Letters Patent is:—

1. An ingot mold provided with a metal receiving cavity and having chilling effect on metal therein decreasing toward the top for a substantial distance by a gradual change in the ratio of perimeter to cross section of the cavity by a gradual change in the contour of the cavity.

2. An ingot mold comprising a mold body provided with a metal receiving cavity, the cavity being concave polygonal in its lower portion and the concavity being gradually reduced in the upward extension of the mold.

3. An ingot mold comprising a mold body provided with a metal receiving cavity, the cavity being concave polygonal in its lower portion and in its upward extension gradually changing to convex polygonal.

4. An ingot mold comprising a mold body provided with a metal receiving cavity, the

cavity being concave polygonal in its lower portion and in its upward extension gradually changing to circular.

5. An ingot mold comprising a mold body provided with a metal receiving cavity, the cavity being concave polygonal in its lower portion and in its upward extension gradually changing to convex polygonal, the change from concave polygonal to convex polygonal being so graduated as to produce a gradually decreasing chill of metal in the cavity toward the top thereof.

6. An ingot mold comprising a mold body, provided with a metal receiving cavity, having in its upward extension a portion of given polygonal contour and a portion equal to not substantially less than one-third of its length, which is of different polygonal contour.

7. An ingot mold comprising a mold body provided with a metal receiving cavity, the cavity tapering on its extreme diameter with an unchanged taper in its upward extension, having the contour of a polygon throughout its lower portion and having a portion of substantial extent adjacent its top of varying polygonal contour in cross section at different points.

In testimony of which invention, I have hereunto set my hand, at Philadelphia, Pennsylvania, on this 27th day of December, 1927.

RADCLYFFE FURNESS.
